[57] CLAIM

The ornamental design for a faucet body, as shown and described.

DESCRIPTION

FIG. 1 is a top perspective view of a faucet body showing my new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The broken line representation of the lift rod in FIGS. 1, 3, 4, 5 and 6 and of the aerator in FIGS. 1, 2, 4 and 5 are for purposes of illustration only and form no part of the claimed design.
